UNITED STATES PATENT OFFICE.

HIRAM B. CANNON, OF PORT HURON, MICHIGAN.

FURNACE OR OVEN.

1,371,774.

Specification of Letters Patent. Patented Mar. 15, 1921.

Application filed March 29, 1920. Serial No. 369,459.

To all whom it may concern:

Be it known that I, HIRAM B. CANNON, a citizen of the United States, residing at Port Huron, in the county of St. Clair and State of Michigan, have invented a certain new and useful Improvement in Furnaces or Ovens, of which the following is a full, clear, and exact description, reference being had to the accompanying drawings.

10 This invention relates to furnaces or ovens, and has for its general object to provide a furnace or oven wherein the heating of articles may be accomplished in a particularly efficient manner. A further and 15 more limited object of the invention is to provide a furnace of this character with a combustion chamber which is adapted to deliver to the article or articles to be heated a maximum proportion of the energy derived from the combustion of the fuel. I 20 secure these and other objects, to be explained hereinafter, through the construction and arrangement of parts shown in the drawings forming a part hereof, wherein 25 Figure 1 represents a central vertical sectional view through such furnace, and Figs. 2 and 3 sectional views corresponding respectively to the lines 2—2 and 3—3 of Fig. 1.

Describing the various parts by reference characters, 1 denotes the front wall, 2 the rear wall, 3 the side walls and 4 the bottom wall of a furnace which is shown as adapted to receive within the top thereof an elongated tank 5 in which metal, such as tin, may be maintained in a molten condition. Beneath the top of the rear wall, the furnace chamber 6 is provided with an opening 7 from which a flue 8 extends. The walls 1—4 inclusive may be of ordinary fire brick having a lining 8^a of insulating brick.

The front wall of the furnace is provided with an opening 9 in which there is mounted an injector 10 by means of which gas, pulverized fuel, or oil may be introduced into a combustion chamber, indicated generally at 11, within the chamber 6 and beneath the tank 5. This combustion chamber comprises a front wall 12, a rear wall 13, a bottom wall 14, side walls 15 and a top wall 16. Between the top and bottom walls and extending from the front wall nearly to the rear wall and between the side walls is a wall 17. This wall is preferably parallel with the top and bottom walls and is supported from the latter wall by means of posts 18. Beneath

the front end of the wall 17, the wall 12 is provided with an opening 19 through which the injector 10 may discharge into the chamber formed by and between the walls 12, 14, 15, and 17. At a short distance rearwardly of the opening 19, there is located a baffle 20, said baffle being preferably triangular in section and having one of its angular corners directed toward the opening 19 and extending between the walls 14 and 17.

The bottom wall 14 is supported upon transversely extending blocks 21, and the wall 16 is provided with slots 22 progressively increasing in width from the rear to the front thereof.

The parts 12—18 inclusive and 20 and 21 are preferably of crystallized carborundum mixed with a small percentage of binding material, such as fire clay, and molded to shape. After the molding operation, the said parts are dried thoroughly and subsequently heated to a temperature of about 3500° F. in order to re-crystallize the carborundum.

In operation, the fuel delivered into the combustion chamber beneath the plate 17 is ignited. The baffle 20 shortens the flame produced by the burning of the combustible mixture confining the flame within the forward portion of the chamber provided below the plate 17. I have found that my carborundum combustion chamber is extremely permeable to heat from within and is capable of radiating heat with extreme rapidity so that, during the progress of the flame and products of combustion from the front to the rear end of the plate 17, a very high proportion of the heat produced by such combustion is radiated by the walls 14, 15 and 17. The combustion chamber 11, being supported within and spaced from the walls of the furnace chamber 6, heats in a most efficient manner the air circulating beneath the bottom and along the sides and ends of the combustion chamber.

Where the escape of the products of combustion into the furnace chamber is not detrimental to the object or objects to be heated, the products may be allowed to escape into the chamber through the slots 22. The progressive increase in the width of the slots from the rear wall 13 to the front wall 12 of the combustion chamber serves to equalize the temperature beneath the bottom of the tank 5, the hotter portions of the products of combustion being discharged

in smaller quantities than the cooler portions of the same.

In addition to its permeability and great heat-radiating qualities, carborundum possesses the following additional qualities which render it peculiarly adapted for the construction of my combustion chamber:—

a. Its high heat-resisting qualities, being decomposable at about 2200° C.;

10 b. Its great tensile and compressive strength which, moreover, is practically invariable throughout all temperature ranges up to within approximately its melting or decomposing point;

15 c. Its low coefficient of expansion whereby it will not crack through sudden and excessive changes in temperature.

Having thus described my invention, what I claim is:

20 1. A combustion chamber having intermediate the top and bottom thereof a partition extending from the front of said chamber toward and spaced from the rear thereof, the top of said chamber being provided with an outlet opening near the front, said chamber being composed principally of carborundum, and means for supplying a combustible mixture into the front of said chamber and beneath said partition.

25 2. A combustion chamber having intermediate the top and bottom thereof a partition extending from the front of said chamber toward and spaced from the rear thereof, the top of said chamber being provided with outlet openings between the rear and the front thereof, said outlet openings increasing progressively in area from the rear toward the front, said chamber being composed principally of carborundum, and means for supplying a combustible mixture into the front of said chamber and beneath said partition.

30 3. A combustion chamber having intermediate the top and bottom thereof a partition extending from the front of said chamber toward and spaced from the rear thereof, the top of said chamber being provided with outlet openings between the rear and the front thereof, said outlet openings increasing progressively in area from the rear toward the front, and means for supplying a combustible mixture into the front of said chamber and beneath said partition.

35 4. A combustion chamber having intermediate the top and bottom thereof a partition extending from the front of said chamber toward and spaced from the rear thereof, the top of said chamber being provided with outlet openings between the rear and the front thereof, said outlet openings increasing progressively in area from the rear toward the front, said chamber being composed principally of carborundum, means for supplying a combustible mixture into the front of said chamber and beneath

said partition, there being a baffle in the front portion of said chamber interposed between the said partition and the bottom wall of said chamber, said baffle being composed principally of carborundum.

5. A combustion chamber having intermediate the top and bottom thereof a partition extending from the front of said chamber toward and spaced from the rear thereof, the top of said chamber being provided with an outlet opening near the front thereof, means for supplying a combustible mixture into the front of said chamber and beneath said partition, there being a baffle in the said chamber and interposed between the said partition and the bottom wall of said chamber.

6. A combustion chamber comprising top, bottom and front and rear walls, a partition intermediate the top and bottom walls and extending from the front wall toward the rear wall and having its rear end spaced from the latter wall, the top wall being provided with outlet openings increasing progressively in area from the rear toward the front wall, blocks supporting the said partition from the bottom wall, a baffle of triangular section interposed between the partition and bottom wall and adjacent to the front end of said chamber, supports for the bottom wall, said combustion chamber, blocks, baffle and supports being composed principally of carborundum, and means for supplying a combustible mixture through the front wall and into the space between the said partition and the bottom wall.

7. A combustion chamber comprising top, bottom and front and rear walls, a partition intermediate the top and bottom walls and extending from the front wall toward the rear wall and having its rear end spaced from the latter wall, the top wall being provided with an outlet opening, a baffle of triangular section interposed between the partition and bottom wall and adjacent to the front end of said chamber, and means for supplying a combustible mixture through the front wall and into the space between the said partition and the bottom wall.

8. A furnace or oven comprising a chamber, and a combustion chamber within the furnace or oven chamber and spaced from the bottom, ends and sides of the first mentioned chamber, the combustion chamber being composed principally of carborundum.

9. A furnace or oven comprising a chamber, and a combustion chamber within the furnace or oven chamber, the combustion chamber being composed principally of carborundum.

10. A furnace or oven comprising a chamber, blocks extending transversely of said chamber and supported on the bottom thereof, a combustion chamber supported on said blocks and spaced from the front, rear and

side walls of the furnace or oven chamber, said combustion chamber and blocks being composed principally of carborundum, and means for supplying a combustible mixture to one end of said combustion chamber.

11. A furnace or oven comprising a chamber, blocks extending transversely of said chamber and supported on the bottom wall thereof, a combustion chamber supported on said blocks and spaced from the sides and ends of the first mentioned chamber, said combustion chamber comprising a top, bottom, and front and rear ends, a partition interposed between the top and bottom of the combustion chamber and extending from the front wall toward and spaced at its rear end from the rear wall of said combustion chamber, the top of said combustion chamber being provided with outlet openings, the front wall of the combustion chamber being provided with an opening beneath said partition, a baffle registering with said opening and in the space between the partition and the bottom wall of said combustion chamber, and means for supplying through the opening in the front wall of the com-

bustion chamber a combustible mixture, the said combustion chamber and the supports and baffle being composed principally of carborundum.

30

12. A combustion chamber for heating by radiation composed principally of carborundum, and means for heating the same interiorly.

13. A combustion chamber for heating by radiation composed principally of carborundum, and means for introducing a combustible mixture into one end of said chamber.

35

14. A combustion chamber having intermediate the top and bottom thereof a partition extending from the front of said chamber toward and spaced from the rear thereof, the said chamber having in the front thereof and below said partition an inlet for a combustible mixture, and a baffle at the rear of said inlet and between the partition and the bottom of said chamber, said chamber being composed principally of carborundum.

In testimony whereof, I hereunto affix my signature.

HIRAM B. CANNON.
